UNITED STATES PATENT OFFICE.

COLEMAN J. MANNING, OF MEDFORD, MASSACHUSETTS.

PRESSURE-GAGE.

SPECIFICATION forming part of Letters Patent No. 723,616, dated March 24, 1903.

Application filed August 12, 1902. Serial No. 119,451. (No model.)

To all whom it may concern:

Be it known that I, COLEMAN J. MANNING, a citizen of the United States, residing at Medford, in the county of Middlesex and State of Massachusetts, have invented a new and useful Improvement in Pressure-Gages, of which the following is a specification.

My invention relates to pressure-gages for steam-boilers and analogous uses and is an improvement in particular upon such gages as employ the Bourdon tubular spring or springs, an example of which is described in Letters Patent of the United States No. 677,674, issued to me July 2, 1901.

The object of my present invention is to facilitate the assembling of the parts of the gage in a complete working combination by making the index-movement adjustable in such manner as to secure greater accuracy and nicety in the practical operation of the gage and also to thereby effect an important saving in time and cost of completing the same.

I attain the object stated by means of the construction and arrangement in respect thereto, which is hereinafter more particularly described, and illustrated in the accompanying drawings, in which—

Figure 1 is a plan showing a pressure-gage of the character referred to, showing an adjustable index-movement constructed in accordance with my present invention, the dial-face being shown as broken away to disclose the interior parts. Fig. 2 is a similar plan of the index-movement alone with its upper plate shown only in dotted outline. Fig. 3 is a perspective of a detached portion of the parts which connect the index-movement with the Bourdon spring and are located on the right of line *z z*, Fig. 2, and as viewed from the right of said line. Fig. 4 is a plan showing one of the Bourdon springs and part of the index-movement connected therewith, as in my said former patent, and is reproduced here for purposes of comparison and illustration only.

The principal parts of the pressure-gage, as illustrated, consist of the case A, the dial B, index C, group of mechanism D, called the "index-movement," and the Bourdon tubular spring E, with which the index-movement is connected and by which it is actuated. The

index-movement by itself comprises a bed-plate F, which, as represented in Fig. 4, has heretofore been firmly and immovably attached to a determined position in the case. When the gage is in a horizontal position with the face upward, as viewed in Fig. 1, plate G of the index-movement appears as an upper plate supported on and secured to standards fixed in plate F, as shown. A vertical spindle H, to which the index C is attached, is supported by plates F and G and arranged to turn therein in the usual manner. A spring I is coiled around said spindle and attached to the same at one end, while the other end is secured to one of the upright standards. This spring offers a slight resistance to the rotation of the spindle in either direction, thereby tending to hold the index in its idle position, or at zero. A small pinion J is also attached to spindle H and is engaged by the teeth K on the sector-lever L, which lever is in two slotted and overlapping parts united by screws, so as to be longitudinally adjustable, and is arranged to rock on a pivoted standard M and by such rocking to impart a proper rotative movement to index C. The outer end of sector-lever L is connected by link N to a projecting ear P on the free end of spring E. The opposite end of the spring is, as usual, connected with the inlet steam-pipe S, and the free end of the spring is actuated by the steam-pressure therein and imparts movement to the index through the link N and the group of mechanism D connected therewith.

It is the usual practice in assembling the various parts of the gage in the case to arrange them therein with reference to a common center, which is the center of the dial B. The index-spindle H coincides therewith, and the arc of the circular spring E is as nearly concentric with the dial as it is practicable to make it. Determinate holes are drilled in the case, whereby the index-movement is located and permanently secured by screws threaded therein through its bed-plate, with the spindle H in the common center. Gages thus constructed, even with highest skill, have proved to be defective as true indicators of pressure and too difficult, laborious, and costly in adjustment. It is very difficult, if not impracticable, to form the tubular springs E of a

uniform and nicely exact length for a given size of gage or diameter of dial. Hence it is necessary when the gage is constructed in the usual manner, as illustrated in Fig. 4, to make 5 a special link N for each gage, thus requiring the exercise of nice skill and the expenditure of much time in properly adjusting the same, and thereby largely increasing the cost. Again, the vibration of the free or working 10 end of the spring is caused by the tendency of the steam-pressure therein to straighten the same. The different degrees of movement of the spring, according to the different degrees of steam-pressure therein, varies the 15 normal arc of the spring accordingly. This variation affects the concentric relation of the parts more or less by throwing the arc out of its true circumferential relation to the common center and disturbs the accuracy of the 20 indications on the dial. No means have hitherto been discovered or employed that would effectively overcome the difficulties in the actuating-spring referred to and save time and expense in completing and adjusting the 25 gages. By long experience as a workman in the manufacture of many thousands of such gages and by many experiments to remedy the defects referred to I have invented and made the simple improvement hereinafter 30 described, that accomplishes the desired purpose and which consists, essentially, in making the index-movement of itself independently adjustable. By so doing I am enabled to make the connecting-link N, as shown in 35 Figs. 1, 2, 3, of uniform lengths and exact duplicates of each other, formed with punch and die, rapidly and cheaply and to be interchangeable in the gages regardless of the variations in the lengths of the tubular springs 40 before referred to. A pin T is driven into one end of the link and extends through the same far enough to reach through the ear P on the end of the spring, as clearly shown in Fig. 3. The opposite end of the link is secured to the sector-lever by a screw, as shown. I make a slot V in the bed-plate F, through 45 which screw W is threaded into the case, with its head overlapping the slot. By slackening screws W and U the bed-plate F by means of the slot V and suitable play on 50 screw U may be swung to a limited extent around screw U, and thus be made adjustable to any deviation in the length of tube E without change in the connecting-link N. Such movement of bed-plate F as it carries with it the pivoted bearing M, around 55 which the sector-lever L rocks, affords a compound adjustment, together with said longitudinally-adjustable lever, whereby the va-

riations before referred to in the arc of the 60 spring may be neutralized in their effect upon the dial indications, and further opportunity to adjust, in respect to the movement of the index, is afforded through such provision for suitable movement of the bed-plate F, in 65asmuch as the axis H is also affected by such movement. Whenever the desired adjustment is thus obtained, a tightening of screws U and W firmly secures the bed-plate F and its attachments to the case. By thus making 70 the index-movement bodily adjustable, substantially as described, the final completion of gages is greatly facilitated, an important saving in expense effected, better results obtained, and the productive capacity of the 75 factory largely increased. With the discovery of such simple and practical means and method of compound adjustment the parts of gages can be assembled and organized for practical operation in less than one-fifth the 80 time required to complete gages in the old way, (illustrated in Fig. 4,) a fact which proves the great usefulness and advantage of the invention.

I claim—

1. A pressure-gage embodying the combination of an inclosing case; a dial; a tubular spring; an index-movement attached to the case so as to be movable, and having the axis of its index thereby made adjustable 85 eccentrically to the dial center; and a link connecting said spring and movement; all substantially as specified.

2. A pressure-gage comprising an inclosing case, a dial, a tubular spring, an index-movement, and a link connecting said spring and movement, the latter having a slotted bed-plate and being thereby made adjustable to 95 springs of varying lengths, connected by links of uniform construction, substantially as and for the purposes specified.

3. A pressure-gage embodying the combination of an inclosing case; a dial; a tubular spring; an index-movement attached to the case so as to be movable, and having the 105 axis of its index thereby made adjustable relatively to the dial center, the movement also including an adjustable sector-lever by which the index is turned, and the pivotal bearing of which lever is also adjustable, 110 with the movement, relatively to the dial center, thereby effecting a compound adjustment of the index; and a link connecting the spring and sector-lever; all substantially as specified.

COLEMAN J. MANNING.
